COMBINATION SOAP HOLDER AND SCRUB BRUSH

Stanley James Tucker, Elkins Park, Pa., assignor to Smith Kline & French Laboratories, Philadelphia, Pa., a corporation of Pennsylvania

Filed Mar. 7, 1966, Ser. No. 1,329

Term of patent 14 years

(Cl. D9—2)

FIG. 1.

FIG. 5.

FIG. 2.

FIG. 6.

FIG. 3.

FIG. 7.

FIG. 4.

FIGURE 1 is a top perspective view of a combination soap holder and scrub brush showing my new design; FIGURE 2 is a top plan view thereof; FIGURE 3 is a front elevational view thereof; FIGURE 4 is a bottom plan view thereof; FIGURE 5 is an elevational view taken from the right side thereof;

I claim:

The ornamental design for a combination soap holder and scrub brush, as shown.
